UNITED STATES PATENT OFFICE.

ROY C. LOGAN, OF TEXARKANA, ARKANSAS.

COMBINATION TOBACCO AND MATCH BOX.

1,235,833.

Specification of Letters Patent. Patented Aug. 7, 1917.

Application filed October 26, 1915. Serial No. 58,027.

To all whom it may concern:

Be it known that I, ROY C. LOGAN, a citizen of the United States, residing at Texarkana, in the county of Miller and State of Arkansas, have invented certain new and useful Improvements in Combination Tobacco and Match Boxes, of which the following is a specification.

My invention relates to receptacles and more particularly to a combination tobacco and match box.

The primary object of my invention resides in the provision of a receptacle or box provided with partitions to form compartments within the main body, the compartments containing tobacco and matches, preferably, though not necessarily.

Another object of my invention resides in the provision of a novel closure for one of the match compartments, the latter being provided with an improved abrasive means for facilitating the striking of matches and having the sides thereof arranged to form a shield to facilitate the lighting of a match.

A further object of my invention resides in the provision of a combined tobacco and match box preferably of the usual construction having the partitions associated therewith in such a manner that different articles or materials may be expeditiously carried therein.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and pointed out in the claims forming a part of this specification.

In the drawings:—

Figure 1 is a side elevational view of the rear of the box;

Fig. 2 is a vertical sectional view of my invention;

Fig. 3 is a transverse sectional view taken on the line 3—3 of Fig. 2 in the direction in which the arrow points;

Fig. 4 is a plan view of the bottom of the box;

Fig. 5 is a top plan view of the box cover open; and

Fig. 6 is a transverse sectional view taken on the line 6—6, of Fig. 2 in the direction in which the arrow points.

Referring more particularly to the drawings in which similar reference numerals designate like or corresponding parts throughout the different views, I provide a box or receptacle including a body 1 formed preferably of metal and having the sides thereof straight and parallel and the ends curved, in cross section. This body is constructed in the usual manner, being formed preferably from one sheet of material, the marginal edges of which are secured adjacent one curved end by bending the edges upon themselves as illustrated by the numeral 2. A bottom 3 is provided and secured adjacent the lower edge of the receptacle in a groove 4 depressed from the inner walls. This bottom is crimped intermediate its ends as illustrated by the numeral 5 to provide a match striker. The extreme lower straight side edges of the body are bent outwardly to provide a flange 6, this flange extending throughout the length of both the lower side edges and one curved edge. The space between the bottom and the lower edge of the body constitutes a compartment for receiving matches, said compartment being closed through the medium of a sliding door 7, the longitudinal edges of which are bent upon themselves to provide engaging flanges 8 for association with the flange 6. Inward movement of the door is limited through the medium of a shoulder 9 adjacent one curved end, the opposite end of the door is curved as illustrated by the numeral 10 and arranged in alignment with one of the curved ends of the box. The compartment just formed can retain matches or other material or else it can be used to facilitate the lighting of a match, for instance a match can be lighted through the medium of the corrugated strip 5, while the sides of the body adjacent the lower end serve as a shield. In order to provide another container for matches within the main body, I have provided an arcuate partition 11, the latter having a circular plate 12 extending laterally therefrom for a purpose to be hereinafter described. The partition 11 is inserted in the body and ar-

5, while the sides of the body adjacent the lower end serve as a shield. In order to provide another container for matches within the main body, I have provided an arcuate partition 11, the latter having a circular plate 12 extending laterally therefrom for a purpose to be hereinafter described. The partition 11 is inserted in the body and ar-

105

ranged so that the free edge of the plate 12 abuts the inner surface of one curved end of the body so that the plate constitutes a bottom for the compartment provided there-
5 above and between the partition 11 and the adjacent curved end of the body. This partition is maintained in position by means 13 such as solder or the like, in the groove 14 and one of the short transverse grooves 10 15. The upper edge of the partition is cut diagonally as illustrated by the numeral 16 to facilitate the removal of a match from the compartment while the front face of the partition is corrugated as indicated by 15 the numeral 17 to provide a match scratch-
ing surface.

For the purpose of closing the receptacle or main body 1 and consequently close the compartment, I have provided a cover 18, 20 the latter having its depending flange 19 hinged as at 20 to the body. The outwardly depressed short grooves 15 provide extending ribs 21 which limit the downward movement of the cover when in an opened position 25 while the transverse depressed groove 14 forms an elongated transverse rib 22 which limits the downward movement of the cover on the box. This construction is illustrated to advantage in the drawings. It is 30 to be understood that the space between the outer surface of the curved partition and the opposite end of the body provides a space for receiving tobacco or other material.

Although I have shown and described the 35 preferred embodiment of my invention, I desire it to be understood that I am not to be limited to the exact details shown, however, I desire that great stress be laid upon the arrangement of the combined box for 40 receiving various materials, the box itself being somewhat similar to the other construction of tobacco boxes now in use. Attention is also directed to the novel compartment and closure therefor at the bottom 45 of the body, which will either serve as a match receptacle or a wind shield.

From the above description taken in connection with the accompanying drawings, it can easily be seen that I have provided a few 50 simple parts that can be cheaply manufac-

tured and assembled and when assembled can be placed upon the market and sold at a minimum cost.

It will be understood that the above description and accompanying drawings comprehend only the preferred embodiment of my invention and that various minor changes in detail of construction, proportion and arrangement of the parts may be made within the scope of the appended claims and 60 without sacrificing any of the advantages of my invention.

Having thus fully described my invention, what I claim as new and desire to secure by Letters Patent, is:—

1. A combination match and tobacco receptacle comprising a tubular body member, a partition dividing said body member into two compartments and secured in said body member intermediate its ends, flanges extending from the edges of one end of the body member, a closure in slidable engagement with said flanges for closing one compartment, an arcuate transverse partition arranged vertically in the other compartment, a plate secured at an intermediate point between the concave face of the arcuate partition and the inner face of the body member, a cover pivotally mounted on the upper end of the body for closing the other 80 compartment.

2. A combined match and tobacco receptacle comprising a tubular body, a partition secured in the body at a point intermediate its ends to provide a lighting compartment and a tobacco containing compartment, a closure for the lighting compartment in slidable engagement with an end of the receptacle, a match containing receptacle disposed in the tobacco containing compartment and secured at one side of the compartment adjacent the open end thereof, and a closure secured to said receptacle for closing said tobacco containing compartment.

In testimony whereof I affix my signature 95 in presence of two witnesses.

ROY C. LOGAN.
